CLAIM

The ornamental design for bag holder, substantially as shown and described.

DESCRIPTION

FIG. 1 is an isometric view of a bag holder, showing my new design;

FIG. 2 is a top plan view thereof;

FIG. 3 is a front elevational view thereof;

FIG. 4 is an isometric view of a second embodiment of a bag holder;

FIG. 5 is a top plan view thereof;

FIG. 6 is a front elevational view thereof.
